CLOSING DEVICE FOR BELT FASTENERS

Curt Matthaei, Offenbach-on-the-Main,
GermanyApplication January 15, 1937, Serial No. 120,773
In Germany February 28, 1936

3 Claims. (Cl. 1—49.4)

The invention relates to a clamping or closing device for belt fasteners, made of V-shaped wire clips with hooked limbs, which has oscillating pressure jaws arranged on each side of the comb holder. The invention has for its object an improvement of these known clamping devices, by providing pressure jaws which, upon insertion of the wire staples, clamps or hooks adapt themselves to the angle of inclination of the staple shanks and come together parallel to each other in ultimate position. The invention has for another object to provide a more useful clamping device of this nature by employing a staple support made in such a manner that an angularly roof-shaped staple holder can be easily and interchangeably fitted thereon.

The object of the invention is attained by the pressure jaws being fixed to the staple support by means of freely expanding and flexible spiral springs. Furthermore the staple support has, according to the invention, a double Y-shaped cross-section and the spiral springs of the pressing jaws are fixed on the lower Y flange whilst the upper Y flange carries the staple holder in a movable and interchangeable manner.

An embodiment of the clamping device according to the invention is shown by way of example in the accompanying drawing, in which

Figure 1 is an isometric view of the clamping device,

Figure 2 is a cross-section with inserted staples before the jaws are closed,

Figure 3 is a cross-section similar to Figure 2 but after the closing and

Figures 4 and 5 are plan and side views, respectively, of the staple holder.

As shown in Figure 1 the pressure jaws 1, 1 are fastened to a staple support 3 by means of freely expanding and flexible spiral springs 2, 2, two springs being preferably arranged on each side. The comb holder 3 is of double Y-shaped cross-section and the spiral springs 2, 2 of the pressure jaws are fastened to the lower Y limbs 4, 4 at the side opposite to the staple holding portion. As shown in Fig. 2, spring 2 is fastened to jaw 1 by means of plugs 11 and 12 having outside threads and a hole or inside thread, respectively, through which screws 13 and 14 are inserted. The oppositely located Y limbs 5, 5 of the support 3 carry the roof-shaped staple holder 6 for the fastening staples or hooks. In this manner, the jaws 1 are held by springs 2 in position on either side of, and substantially parallel to staple support 3, as shown in Fig. 2; since the springs expand as well as bend, the jaws are

permitted to assume positions independent of the general direction of the springs. The jaw position is preferably determined by the staple support or holder, and the staples themselves. Further, the springs exert in closed jaw position (Fig. 3) a downwardly directed force component which is transmitted to the staples, and promoting the penetration of downwardly curved staple points. The roof-shaped staple holder 6 (Figure 4) has slots 7 transversely to its longitudinal direction, to take the staple bend (Figures 2 and 3. The turned over lips 8 of the staple holder engage the upper Y limbs 5, 5 of the staple support 3 whereby the staple holder 6 is held in the correct position between the pressing jaws for the insertion of the fastening staples or clips. In the clamping device according to the invention staple holders 6 of any width may be used so that, for example, if belts are used which are wider than the pressing jaws 1, the number of staples necessary for the whole width of the belt may be inserted into holder 6 which can be moved along supports 3 for application of the jaws to consecutive groups of staples. The hooks are held in the usual way by a pin which is adapted to the flattened part of the roof-shaped comb.

For very thin belts hooks are made of very thin wire for the insertion of which a tool especially designed for the purpose has hitherto been necessary. This is no longer required with the clamping device according to the invention, since it is merely necessary to use a staple holder with suitably narrower subdivisions for the thin hooks, fitted to staple support 3.

The clamping device according to the invention is preferably operated by means of a vise, the jaws of which engage the outside of the pressure jaws 1 of the clamping device. Naturally the pressing together of the pressing jaws is possible in many other ways. The operation of the clamping device according to the invention can be easily seen from Figures 2 and 3. Before the commencement of the staple insertion, the pressing jaws 1 rest on the staple support or staple holder. Upon pressure being exerted, the spiral springs 2 expand as well as bend between the pressing jaws 1 and the flange portions 4 of the staple support 3. As the holder 6 serves in this movement of the spiral springs 2 and of the pressing jaws at the same time as support for the pressure jaws, the position of the inner surfaces of the pressing jaws adapts itself during the whole pressing-in process to the angle of inclination of the staple shanks. Consequently the insertion of the hooks always

takes place with the pressure surfaces of the jaws fully applied to the hook shanks up to the time when a complete parallel position is reached after the pressing in is completed (Figure 3).
5 The belt into which the hooks are pressed in is omitted from the drawing for the sake of clearness.

What I claim is:

1. Device for inserting wire staples of the hooked limb type used as belt fasteners, comprising a support for said staples, a pressure jaw, and flexible as well as expanding spring means fastened to said support and said jaw, extending substantially in the direction of said limbs and 10 freely holding said jaw in position relatively to said support.
- 15 2. Device for inserting wire staples of the type

used as belt fasteners, comprising a support, means for removably mounting a staple holder on said support, two pressure jaws, and spiral springs fastened to said support below said holder, and to said jaws and extending at an angle 5 to each other freely to hold jaws one on each side, respectively, of said holder.

3. Device for inserting wire staples of the type used as belt fasteners, comprising a support having an upper and a lower flange, means for slidably mounting a staple holder on said upper flange, spiral springs mounted on said lower flange extending upwardly on either side of said holder, and pressure jaws fastened to said springs, one on either side, respectively, of said 10 holder.
